UNITED STATES PATENT OFFICE.

LEON B. CONANT, OF CAMBRIDGE, MASSACHUSETTS, ASSIGNOR TO GEORGE M. CONANT,
OF BRIDGEWATER, MASSACHUSETTS.

MOLD FOR COMBINATION HEELS.

Application filed July 12, 1926, Serial No. 121,958. Renewed April 28, 1927.

This invention relates to the molds in which a rubber tread is vulcanized to a fibre base; and it has for its objects, first, the reduction in the cost of producing the 5 molds; second, the effecting of means for adapting the same mold for different thicknesses of bases; and, third, the shaping of the mold in a manner to produce the best results in the process of vulcanization.

10 For achieving the first result, I cut the centreplate off on the shoulder which supports the base, and provide a small number of pins for the proper positioning of the heel base on the shoulder. For the second improvement, I provide the backplate with removable stops, which, by their descent upon the centreplate, limit the compression of the base; and for the third improvement, I give the base-supporting shoulder a downward inclination which prevents its edge 15 from cutting into the base.

In the drawings forming part of this specification, Fig. 1 is a cross section of the complete mold. Fig. 2 is a plan view of 20 the centreplate thereof. Fig. 3 is a cross section of the centreplate designed for a pre-shaped base.

As shown in Fig. 2, the centreplate 1 is 25 formed with a cavity 2 shaped for properly molding the rubber tread; the face plate supporting the same being shown in Fig. 1. This centreplate has its upper surface flush with the shoulder 3 upon which the edge of the heel base 8 is to rest. Previous to this invention, the shoulder was made entirely 30 flat and with a right-angled edge. This I have discovered was a very faulty construction, for the reason that such sharp edge during the process of vulcanization, was so forced into the leather by the heavy pressure incident to the process, as to impart 35 heat thereto more extremely than elsewhere, and thereby to char the leather and frequently ruining the bases.

40 But, by having the shoulder slope downward toward the interior of the mold to coincide with the curvature given to the under surface of the heel base, all such injurious effects were entirely avoided.

45 I prefer not to extend the centreplate above the level of the shoulder 3 as is shown in Fig. 3, but to position the heel bases thereon by means of a series of pins 4 rising from the centreplate, as shown in Figs 1 and 50 2; the dotted line in Fig. 2 indicating the

edge of a heel base. It is evidently far less expensive to drill a few holes in the centreplate and to drive pins therein, than it is to form the type of centreplate shown in Fig. 3.

To facilitate the introduction of the heel bases into the centreplate, the surfaces of the pins 4 are filed away on the sides adjacent the shoulder 3 in order to have them flare outwardly, as shown in Fig. 1. In 60 case the centreplate is formed as illustrated in Fig. 3, its surfaces adjacent the shoulder 3 are also made to flare outwardly. This figure shows a preshaped heel base located 65 therein, as 9.

Because of the heavy pressure required in the process of vulcanization, it is unwise to limit the descent of the backplate by the pins 4, for the reason that the latter would soon become flattened and injured thereby. 70 Therefore, strips 6 are attached to the upper surface of the centreplate or to the under surface of the backplate, but preferably to latter, as shown in Fig. 1, screws 7 being 75 used as the means of such attachment. By 80 thus having the strips removable, thinner or thicker ones can be substituted for the purpose of adapting the same mold for different types and styles of heel bases.

85 What I claim as my invention is:

1. A mold for combination heels, comprising a centreplate having a shoulder flush with the upper surface thereof, a backplate co-operating therewith, and means for positioning a heel base relative to the centreplate, said positioning means consisting of pins projecting from one of said plates.

90 2. A mold for combination heels, comprising a centreplate having a shoulder flush with the upper surface thereof, a backplate co-operating therewith, and a series of pins rising from the centreplate spaced from the edge of the shoulder for positioning the heel bases thereon.

95 3. A mold for combination heels, comprising a centreplate having a shoulder flush with its upper surface, means for positioning the heel bases relative to said shoulder, a backplate, and means for limiting the descent of the latter.

100 4. A mold for combination heels, comprising a centreplate having a shoulder flush with its upper surface, pins projecting from the centreplate for positioning the heel bases thereon, a backplate, and means for limiting 105 110

the descent of the latter consisting of strips removably attached to one of the adjacent surfaces of the centreplate and backplate.

5. A mold for combination heels, comprising a centreplate having a shoulder flush with its upper surface, pins rising from the centreplate spaced from said shoulder, a backplate, and strips removably attached to the latter, the means of attachment consisting of screws penetrating the backplate and strip.

10. A mold for combination heels, comprising a centreplate having a shoulder for the support of the edges of the heel bases, means 15 for centering the bases thereon, and a back-

plate, said shoulder sloping downward toward the interior of the mold.

7. A mold for combination heels, comprising a centreplate having a shoulder for the support of the edges of the heel bases, means 20 for centering the bases thereon, and a backplate, said shoulder sloping downward toward the interior of the mold, and said centering means having their surfaces adjacent the shoulder flaring outwardly. 25

In testimony that I claim the foregoing invention, I have hereunto set my hand this 25th day of June, 1926.

LEON B. CONANT.
